SPOOL HOLDERS FOR SEWING MACHINES

John Platt, Dalmuir, Glasgow, Scotland, assignor to The Singer Manufacturing Company, Elizabeth, N.J., a corporation of New Jersey

Application April 12, 1956, Serial No. 577,719

Claims priority, application Great Britain March 19, 1956

4 Claims. (Cl. 112—218)

This invention relates to sewing machines, and more particularly, to a spool pin support for the needle thread supply of a sewing machine.

It is an object of this invention to provide a spool pin support adapted to position a spool pin on a sewing machine frame in an exposed position favorable to the delivery of thread from a spool thereon to the stitch forming instrumentalities while the machine is in use, and in an unexposed position when the machine is readied for transportation or for storage.

A more specific object of this invention is to provide a spool pin support formed as a part of a retractable lifting handle for a sewing machine frame.

With the above and other objects and advantages in view as will hereinafter appear, this invention comprises the devices, arrangements and combinations of parts hereinafter described and illustrated in the accompanying drawings of a preferred embodiment in which:

Fig. 1 represents a front elevational view of a sewing machine frame having the spool pin support of this invention applied thereto.

Fig. 2 is an enlarged top plan view of a portion of the sewing machine frame illustrated in Fig. 1, and

Fig. 3 represents a cross-sectional view taken substantially along lines 3—3 of Fig. 2, showing in full lines the spool pin in exposed or operative position and in dotted lines the spool pin in unexposed or retracted position.

Referring to the drawings, this invention is illustrated as applied to a sewing machine having a conventional frame including a bed 11, from which rises a hollow standard 12 supporting a hollow bracket-arm 13. The free extremity of the bracket-arm is closed by a face plate 14 and the top of the bracket-arm and standard is closed by a top cover plate 15 secured in place by fastening screws 16—16.

Formed transversely of the top cover plate are spaced vertical slots 17—17 and a recess 18 in the front portion between the slots 17 to accommodate a U-shaped lifting and carrying handle 19. The lifting handle is of the type disclosed in the Peets et al. Patent No. 2,678,011, May 11, 1954, to which reference may be had for a more complete disclosure. For the purpose of the present invention it is sufficient to understand that the handle is preferably formed of a single sheet metal stamping bent into a U shape comprising a pair of spaced substantially parallel arm portions 20 and 21 fitted each into one of the cover plate slots 17—17 and joined by a hand grip portion 22. The under surface of the top cover plate 15 adjacent each of the slots 17—17 is formed with downwardly extending lugs 23 defining therebetween a bearing into which is seated trunnion pins 24—24 fitted one into each of the handle arms 20 and 21. As best illustrated in Fig. 5, a leaf spring 25, secured beneath the top cover as by a fastening screw 26, is arranged to bear upwardly beneath each of the handle arms 20 and 21 for the dual purpose of maintaining the trunnion pins in position between the bearing lugs and also for urging the handle into either a fully opened or fully closed

2

position. When in opened position as illustrated in dotted lines in Figs. 1 and 3, the arms 20 and 21 of the handle extend substantially normal to the top cover plate and the hand grip portion 22 is disposed in an operative position in that it is exposed for use in shifting the sewing machine. When in closed position, the handle is inoperative as a lifting means since it is almost entirely buried into the top cover plate with the handle arms 20 and 21 being disposed within slots 17—17 and the handle grip in the recess 18 of the top cover plate.

The spool pin support of this invention is provided by means of a spool supporting platform 30 formed as an extension of the arm portion 21 of the handle, to which platform a spool pin 31 is secured. The platform 30 joins the upper edge of the arm portion, considered when the handle is closed as illustrated in full lines in the drawings, and the juncture of the platform with the arm portion 21 is preferably continuous along the arm portion from a point intermediate the ends of the arm portion to the juncture of the arm portion with the hand grip portion. The platform 30 is bent outwardly, that is in a direction opposite that of the other arm portion 20 of the handle, in substantially a right angle to the arm portion 21 so that when the handle 19 is in closed position the platform 30 provides a substantially horizontal platform overlying the top cover plate from which the spool pin 31 extends vertically upward as best illustrated in Figs. 1 and 3. The spool pin 31 is thus disposed substantially normal to the U-shaped carrying handle and will occupy an effective spool supporting position when the handle is turned into its inoperative position. The full line position of the handle 19 in the drawings represents the usual position of the handle during operation of the machine, in which position, the spool pin 31 and its supporting extension are disposed in position to accommodate a spool of needle thread. When the handle is moved into its opened position, as illustrated in dotted lines in Figs. 1 and 3, in which it is effective to aid in transportation or bodily movement of the sewing machine, the platform 30 will move to a vertical position and the spool pin will extend rearwardly of the sewing machine in a substantially horizontal position. A coil spring 32 which fits snugly over the spool pin may be used to offer sufficient resistance to the removal of a thread spool from the spool pin so as to minimize the possibility of a spool of thread slipping accidentally from the spool pin while the machine is being carried by the handle 19.

In addition to its use in carrying the sewing machine, the handle 19 serves as a useful aid in raising and lowering the sewing machine when the machine is housed in a drop-head sewing machine cabinet. Drop-head machine cabinets, i.e., those with provision permitting the shifting of the sewing machine to a lowered position beneath the level of the cabinet top when not in use, are almost universally constructed so that the sewing machine may be tipped forwardly into lowered position. The U.S. patent of Marsac No. 2,527,319, Oct. 24, 1950, is illustrative of this type of drop-head cabinet arrangement and may be referred to for a more detailed description thereof.

When a sewing machine is tipped forwardly in a drop head sewing cabinet, clearance between the sewing machine and the cabinet is most critical at the top front edge or corner of the sewing machine. It is for this reason that the conventional locations for the spool pin of a sewing machine are either at the center of the machine frame or at the top rear edge thereof. A spool pin 33 illustrated in Figs. 1 and 3 of the drawings is of the conventional variety, being set into a boss 34 formed at the rear edge of the top cover plate.

It will be apparent that the spool pin arrangement of

this invention provides for a more convenient location of the spool pin nearer the operator during operation of the machine than is possible with a conventional spool pin fixed in the machine frame. When the machine is to be lowered into a drop head cabinet, shifting of the handle 19 to its operative position will automatically position the spool pin out of the zone of critical clearance between the sewing machine and the cabinet.

The spool pin arrangement of this invention thus finds utility as the sole spool pin of a single needle sewing machine. In addition, the instant construction is particularly advantageous in instances where two needles are used threaded with different colors or types of thread. In many of the present day family sewing machines a decorative seam may be made having two needle threads simply by providing a pair of closely spaced needles threaded with different threads and both cooperating simultaneously with the same loop taker in the formation of stitches. With this type of two needle work, the spool pin arrangement of this invention provides a highly satisfactory solution to the otherwise perplexing problem of how to provide separate spool pins for the two different spools of needle thread. The spool pin 31 of this invention is disposed, when in operative position, at the opposite side of the sewing machine from the conventional fixed spool pin of the machine, and therefore, a minimum of interference will occur between the two thread spools supported thereby, the spool pin 31 does not hamper the usefulness of the handle 19 in lifting or carrying the sewing machine, and the relationship of the spool pin 31 and the handle 19 is such that the spool pin will be shifted automatically out of a position of interference when the machine is to be raised or lowered in a drop sewing machine cabinet.

Having thus set forth the nature of the invention, what I claim herein is:

1. In a sewing machine having a frame, a carrying handle, means for pivoting said carrying handle to said sewing machine frame for turning movement from an upright operative position to an inoperative position

35

40

against said sewing machine frame, a spool holder including a spool supporting pin, and means for fixing said spool supporting pin on said handle in an upright position when said handle is turned to said inoperative position.

- 5 2. The device as set forth in claim 1 in which the spool holder comprises a spool supporting platform, means for securing said platform to said carrying handle, a spool pin, and means for securing said spool pin substantially normal to said platform.
- 10 3. The device as set forth in claim 1 in which the carrying handle comprises a U-shaped member including spaced arms pivoted to the sewing machine frame and joined by a hand grip portion, and in which the spool holder comprises a spool supporting platform, means for securing said spool supporting platform to one of the arms of the carrying handle, and means for fixing said spool pin on said spool supporting platform substantially normal to the U-shaped carrying handle.
- 15 4. In a sewing machine having a frame, a carrying handle comprising a U-shaped member including spaced arms joined by a hand grip portion, means pivoting said handle to the top of the sewing machine frame for turning movement of the hand grip portion to an inoperative position against the front of the sewing machine frame, a spool supporting pin and means for fixing said spool pin on said handle adjacent the juncture of said hand grip portion with one of said spaced arms and in an upright position adjacent to the front of the sewing machine frame when said handle is turned to said inoperative position.
